UNITED STATES PATENT OFFICE.

ARTIE C. CARLSON, OF VALPARAISO, INDIANA, ASSIGNEE, BY MESNE ASSIGNMENTS,
TO THE NORTHERN TRUST COMPANY AND HAROLD H. ROCKWELL AS TRUSTEES.

NEWSBOY-WAGON BODY.

Application filed March 29, 1926. Serial No. 98,303.

My invention relates to improvements in newsboy wagon bodies and it more especially consists of the features pointed out in the claims.

5 The purpose of my invention is to provide a wagon body specially adapted for newsboy services in which increased capacity is secured through the use of folding side-board extensions which are hinged to the 10 upper edges of the sides so as to be folded inwardly or folded outwardly on approximately a horizontal plane and also at an angle between these two extremes; and that provides means for limiting extreme or intermediate positions of the extensions.

15 With these and other ends in view, I illustrate in the accompanying drawing such instances of adaptation as will disclose the broad underlying features without limiting 20 myself to the specific details shown thereon and described herein.

Figure 1 is a side elevation of a complete wagon.

Fig. 2 is a rear end elevation of Fig. 1, 25 with the wheels omitted.

Fig. 3 is a cross section of the body looking toward the rear end.

Fig. 4 is a plan view of a corner of the body, partly in section.

30 In practically carrying out my invention, I may use such alternative constructions as are found necessary to meet varying conditions as to sizes, dimensions, etc., without departing from the spirit of my invention.

35 The body is composed of side boards 1 whose ends are rabbetted to receive between them a front cross member 2 and a rear cross member 3. The sides 1 may have grooves on their inner faces near their bottom edges 40 into which transversely placed floor boards 4 are positioned. The sides and end members of the body are held in engagement by corner brackets 17 formed of sheet metal. The body is supported above the wheels by 45 U-shaped members 5 and 6. The rear axle support is braced on the body by bars 9 that are secured to the sides 1.

50 The front of the body has a steering fork 12 which is held at an angle by the connecting bar 13. The body is attached to the support 5 by a suitable king pin, and fifth wheel plates 8 are positioned between the support 5 and the front end 2 of the body.

55 A brace 7 reaches from a cross member of the steering frame 12 to the floor boards 4.

Axes 10 and wheels 11 complete the under structure of the body. The steering is done by handle 14 pivotally attached at 16 to the steering fork 12. This handle has bearing on a bracket 15 in line with the center of 60 the king pin.

The under structure may be varied as widely as desired, for the reason that the body features are equally applicable to any 65 desired type of such structure.

In Fig. 1 the folding side extensions 18 are broken, the forward half being shown in a horizontal position, and the rear half raised at an angle, while the vertical position is shown by dotted lines. These side 70 extensions are reinforced at their ends by U-shaped sheet metal plates 19 which are pivoted at 22 to upwardly extending projections of the corner brackets 17 and the extensions 18 are held in horizontal positions by the braces 23.

The upper ends of these braces are pivoted at 25 to the extensions 18, and their lower ends are provided with headed pins 24, shown in Fig. 4. These pins slide in 80 slots 20 of the corner brackets 17. The brackets 17 are bent outward, as shown in Fig. 4, so as to provide sliding room for the head of the pins 24. These heads prevent the pins being pulled out of the slots 85 20. To support the extensions 18 at an angle, as shown in Fig. 2, lateral notches 21 are formed in the slots 20. As shown, notches 21 are located at the upper ends of the slots 20.

If it is desired to hold the extensions 18 at other angles additional notches 21 (not shown) may be provided. Along the top edge of the front end 2 and the rear end 3 a cover strip 26 may be placed to cover 95 notches formed in the top edge of these end members to receive the heads of bolts for securing same to the under supports 5 and 6. In the former case serving as a king pin, and in the latter case as a rigid securing 100 means.

Through the use of my present construction I am able to dispense with nails of all kinds, thereby securing a more rigid and serviceable structure than is otherwise attainable. The parts may be secured to each other by the use of rivets, stove bolts, etc. If the latter are used instead of rivets or ordinary wood screws the assembled relation of the body parts may be maintained in its 110

original rigidity by simply tightening the stove bolts to compensate for any shrinkage that may take place.

Extra capacity for newspapers is secured by 5 reason of the side extensions when these extensions are folded outward, as shown in Fig. 3. This arrangement of parts permits the piling of folded newspapers on the floor boards lengthwise of the body for the full depth of 10 the sides, after which folded newspapers are placed crosswise of the body in one or more stacks as desired, the side extensions 18 supporting the outer ends of the newspaper stacks. These stacks may fill the length of 15 the body and, if needed, a rope may be passed over the same and underneath the body lengthwise thereof to hold the stacks in place, thus insuring a capacity that is quite beyond any form of newsboy delivery 20 wagon hitherto available.

If the quantity of papers does not exceed the depth of the body, the extensions 18 may be folded inwardly, as shown in Fig. 2, in which position the papers are held against 25 being blown away.

What I claim is:

1. In toy wagon bodies; suitable end members, suitable sides, corner brackets for holding the sides and ends in engagement with 30 each other said brackets having slots therein, side extensions pivoted to the upper end of the brackets, and braces pivoted to the ends of the extensions and adapted to be held in sliding relation in the slots of the brackets.
2. In toy wagon bodies, a pair of side body members, a pair of end body members against which the side members are posi- 35

tioned, slotted plates secured to the corners of the body for holding the side and end members in assembled relation, extensions 40 for the sides of the body adjustably held in different positions in relation to the sides by supporting braces slidable in the slotted plates, and means on such plates for limiting the movement of the braces and permitting the sides to swing through an arc of approximately 180 degrees.

3. A toy wagon body comprising sides ends and floor boards, corner brackets for holding these parts in rigid assembled relation, side extension members, reinforcing metal ends for said extensions, means for pivoting said ends to the brackets, braces pivoted to these metal ends, and means for holding the free ends of the braces in sliding relation on the brackets to permit the sides to be moved through an arc of approximately 180 degrees.

4. In toy wagon bodies, a rigid frame composed of ends, sides and floor boards 60 held between the sides, pivoted extensions for the sides, end braces for the extensions, guiding means for the end braces, and limit slots in the said means for holding the side extensions in horizontal positions approximately 180 degrees apart, and limit notches in the guiding means adapted to rigidly hold the end braces in an intermediate position so that the side extensions are held at an angle to the horizontal which is less than 90 65 degrees.

In testimony whereof I affix my signature.

ARTIE C. CARLSON.
